SINGLE SHEET SHIRT PROTECTOR

Victor Akers, Albany, Calif.

Application August 20, 1948, Serial No. 45,592

2 Claims. (Cl. 223—71)

1

The invention, in general, relates to the laundry art, and more particularly relates to means for application to a laundered shirt for protecting the same from any likelihood of becoming wrinkled, crushed or otherwise damaged in transit from the laundry to the home of the patron.

Heretofore, various types of shirt boards or forms have been devised for use in the preparation of a laundered shirt for packaging and transporting from the laundry to the patron in order to avoid as much wrinkling or crushing of the laundered shirt as possible in transit. In a majority of instances, separate shirt forms and collar supporting elements are utilized by the laundryman for these purposes although some of these prior protectors have included the collar supporting element as an integral part of the shirt form proper. In general, substantially all of these prior shirt protectors and collar supports are deficient at least in so far as properly supporting the laundered collar and numerous complaints and oftentimes loss of customers have resulted because of the badly wrinkled and even crushed condition of the shirt collar when received by the patron. Some of the difficulty encountered in the packaging and transporting of the laundered shirt heretofore is attributable to the lack of rigidity or strength afforded in the bundles containing a number of the laundered shirts arranged in superimposed relationship, which is the usual mode of delivery of laundered shirts. In addition to the foregoing disadvantages inherently residing or occurring from the use of substantially all types of these prior shirt protectors, the employment of either type of such former devices; namely, either the two separate element protector including separate shirt form proper and separate collar supporting element or the integral unit of shirt form and collar element is appreciably costly to the laundryman not only because of the increased time involved in making the insertions of the protector into the laundered shirts but also because of the additional cost of manufacture of such prior devices. The present invention is directed to the provision of a unitary shirt protector form containing an integral collar supporting element which obviates all of the foregoing disadvantages of prior devices of this character.

A primary object of the invention is to provide an improved shirt protector form which affords means for holding or maintaining the body and collar of a laundered shirt in its freshly

laundered state under all conditions of transit to the patron after leaving the laundry.

Another important object of my invention is to provide a shirt protector form of the indicated nature which is additionally characterized by its capacity of affording the requisite rigidity and strength to packages of laundered shirts containing the shirts in superposed relationship to withstand appreciably heavy weights thereon or other abuse and avoid all likelihood of wrinkling, crushing or otherwise deleteriously affecting the laundered shirts while in transit from the laundry to the patron.

A still further object of the present invention is to provide an improved shirt protector form of the aforementioned character which can be inserted in operative position into a laundered shirt more readily and rapidly even by the unskilled.

20 Another object of my invention is to provide a shirt protector form of the indicated nature which combines the shirt form proper with the collar supporting element as an integral unit and which can be manufactured at a much lower cost to the user.

25 A still further object of the present invention is to provide an improved shirt protector form of the aforementioned character which affords the requisite protection to freshly laundered shirts without the necessity of using a shell or box for the shirt, heretofore commonly employed, thus eliminating extra handling as well as appreciable card-board stock.

30 Other objects of the invention, together with some of the advantageous features thereof, will appear from the following description of a preferred embodiment and a modified embodiment of my invention which are illustrated in the accompanying drawings. It is to be understood, however, that I am not to be limited to the precise embodiments shown, nor to the precise arrangement of the various elements thereof, as my invention, as defined in the appended claims, can be embodied in a plurality and variety of forms.

35 Referring to the drawings:

Fig. 1 is a perspective view, partly in dash and partly in full line showing, of a preferred embodiment of the invention in operative position in a laundered shirt.

40 Fig. 2 is a perspective view, partly in dash and partly in full lines, of a modified embodiment of the invention in operative position in a laundered shirt.

45 Fig. 3 is a fragmentary, sectional detail of the

preferred embodiment of the invention is fitted beneath the collar of a laundered shirt, this view being taken on the line 3—3 of Fig. 1.

Fig. 4 is a fragmentary, sectional detail of the modified embodiment of the invention shown in Fig. 2, as fitted on the inside of the shirt collar of a laundered shirt adjacent to the neck-band of the shirt, this view being taken on the line 4—4 of Fig. 2.

Fig. 5 is a plan view of the preferred embodiment of the invention.

Fig. 6 is a plan view of the preferred embodiment of the invention in slightly alternate form.

Fig. 7 is another plan view of the preferred embodiment of the invention in another alternate form.

Fig. 8 is a plan view of the modified embodiment of my invention which is illustrated in Fig. 2.

Fig. 9 is a plan view of the modified embodiment of the invention similar to the view of Fig. 8 but in slightly alternate form.

Fig. 10 is a fragmentary plan view of still another alternation of the modified embodiment of the invention, which is illustrated in Figs. 2 and 8.

In its preferred form, the combined shirt protector form of my present invention preferably comprises a collar supporting element having transverse score lines therein to facilitate fitting the same about a shirt collar, a generally rectangular body portion; the end of said body portion adjacent to the collar supporting element being straight at its center and being inclined on its lateral extremities to define tapered openings between the body portion and the collar supporting element, together with a pair of spaced score lines extending in parallel relationship between said collar supporting element and said body portion to afford bending and folding of the collar supporting element in one or the other of two places with respect to said body portion enabling the collar supporting element to be folded and fitted in an upright position under either a low or a high collar of a shirt.

The modified embodiment of my present invention preferably comprises a collar supporting element similar to that of the preferred embodiment but containing a window therein, a body portion similar to that of the preferred embodiment, together with a reduced portion joining the collar supporting element to the body portion, a score line at the juncture of the reduced portion and the body portion, and a pair of score lines in spaced parallel relationship between the collar supporting element and the reduced portion to enable folding of the collar supporting element on the outside and over the top of the back of a shirt collar and fitting the same on the inside and about the shirt collar adjacent to the neck-band of the shirt; said collar supporting element being notched adjacent to its juncture with the reduced portion to enhance the folding of the collar supporting element toward the reduced portion and to increase its supporting character.

As particularly illustrated in Figs. 1 and 5 of the annexed drawings, the preferred embodiment of my present invention is exemplified in a blank, designated generally by the reference numeral 11, which is generally rectangular in shape and which preferably is fabricated of cardboard. The blank 11 is cut away adjacent to one longitudinal extremity thereof on straight

lines 12 and 13 as well as on oblique or bias lines 14 and 16 to remove or cut away small, generally triangular portions of the blank and thus to define a collar supporting element 17 as well as a body portion 18. The body portion 18 is thus provided with a straight end 19, a pair of straight, substantially parallel sides 21 and 22, and an irregular opposite end consisting of a pair of oblique portions 14 and 16 on opposite sides of a straight central portion. Moreover, the collar supporting element thus provided by cutting blank 11 as indicated is an elongated rectangle relatively narrow in width and to enable effective bending and fitting of the collar supporting elements in operative position about a shirt collar, a plurality of spaced score lines 20 are formed transversely of the collar supporting element, as clearly shown in Fig. 5.

In accordance with the present invention, the blank 11, which constitutes the base from which the collar supporting element 17 and body portion 18 of my shirt protector form is made, is initially cut to a requisite width to afford a relatively long collar supporting element 17 whereby, when disposed about and beneath the collar 26 of a laundered shirt 27, see Fig. 1, the opposite ends 28 and 29 of the collar supporting element lie in close proximity to the lapels 30 of the laundered shirt collar. The result is that substantially all of the laundered collar is supported in raised position with respect to the balance of the laundered shirt yet without deleteriously affecting the laundered collar lapels 30 which lie flat to the body of the shirt. In view of this requisite width of the blank 11 to afford the desirable length of collar supporting element 17, as above indicated, and in view of the preferred rectangular shape of the shirt protector form, the body portion 18 of the form is cut somewhat wider than the normal width of a normally folded laundered shirt. Accordingly, longitudinally extending score lines are preferably formed in body portion 18 of the protector form in substantially parallel arranged pairs 31, 32 and 33, 34 at opposite sides of the blank 11 to define flaps 35 at each side of the body portion. Upon insertion of my improved shirt protector form into a freshly laundered shirt, the body portion 18 is laid against the back of the laundered shirt and the collar supporting element folded on either the score line 26 or 37 formed in the blank 11, depending upon the height of the attached collar on the laundered shirt, which extend in spaced, substantially parallel relationship between the collar supporting element and the body portion of the blank and thus the collar supporting element 17 is partially raised for insertion beneath or under the folded collar 26 of the shirt and ultimately raised to a position normal to the body portion 18 to support the collar 26 in raised position with respect to the balance of the shirt. At the same time, of course, the operator bends or curves the elongated collar supporting element on the score lines 20 to position such element about the collar bringing the ends 28 and 29 thereof in close proximity to the lapels 30 of the collar 26. Thereafter, the laundered shirt is folded in the customary manner, and the flaps 35 of the body portion 18 folded under, first by folding on the score lines 32, 33 and then on score lines 31, 34 to bring the flaps 35 to the position indicated in Fig. 1 of the annexed drawings. This whole operation of inserting the improved, preferred embodiment of my shirt pro-

tector form in operative position in a laundered shirt is a matter of two or three seconds. If the attached collar to a laundered shirt is a high collar, the collar supporting element is folded on score line 37 while if the attached collar 26 of the shirt is average, or customarily low, the collar supporting element 17 is folded on the perforated score line 36 to compensate for the different height of collar. It is to be remarked that I preferably form the transverse scorings of the collar supporting element 17 with embossed scorings, and the two parallel score lines 36 and 37 with perforated scorings. The longitudinally extending score lines in the body portion 18 may be either perforated or embossed, as desired.

In Fig. 6 of the annexed drawings, I have illustrated an alternate form of the preferred embodiment of the present invention. This form is substantially the same as the embodiment depicted in Fig. 5 with the exception that it is made for application to only one size or height of collar attached to a laundered shirt since only one score line 36' is provided at the juncture of the collar supporting element 17 and the body portion 18 of the shirt protector form. Moreover, the body portion can be narrower than the body portion of the embodiment of Fig. 5 altho it preferably is of the same width in order that the collar supporting element 17 be of requisite length properly to support the major portion of the collar 26 of the laundered shirt. A slightly different alternation of the preferred embodiment of the invention is illustrated in Fig. 7 in that except for the inclusion of two notches 40 and 40' in the collar supporting element 17 adjacent to its juncture with the body portion 18 it is similar to the embodiment of Fig. 5. The provision of the notches 40 and 40' facilitates folding of the collar supporting element toward the body portion when inserting the protector form into a laundered shirt having an attached collar 26 of greater height than average, and enhances the supporting quality of the element 18 with respect to shirts having such higher collars.

A modified embodiment of the present invention is illustrated in perspective in Fig. 2 of the drawings and in plan view in Fig. 8. This modification is generally similar to the preferred embodiment of the invention but is devised for insertion in a laundered shirt with the collar supporting element thereof disposed inside of the attached collar of the shirt adjacent to the neck-band thereof. To this end, I provide a generally rectangular shape blank 111 which preferably is so stamped or cut on straight lines 112 and 113 as well as on bias or oblique lines 114 and 116 to define the collar supporting element 117 and a body portion 118, together with a reduced portion 118' connecting the collar supporting element and the body portion, as shown. The body portion 118, thus provided, has a straight end 119, a pair of straight sides 120 and 121 and an irregular opposite end having two oblique portions 114 and 116 and an intermediate straight central portion. The collar supporting element 117, formed by stamping or cutting the blank 111 as above indicated, is an elongated, rectangular shape and preferably is notched, as at 140 and 140' on opposite sides of the reduced portion 118' of the shirt protector form. In addition, the elongate collar supporting element is formed with an elongated window or opening 125 therein in order that the customary laundry mark delineated on the neckband of the laundered shirt may readily be discernible. As in the case of the preferred

embodiment of the invention, the collar supporting element preferably is formed with a plurality of spaced scorings therein, conveniently by means of embossed score lines, to facilitate bending or folding the element about the inside of the neck-band of a laundered shirt.

The body portion of the modified embodiment of the invention is in all respects similar to the body portion of the preferred embodiment shown in Fig. 5 in that it is formed with a series of longitudinally extending score lines, either embossed or perforated as desired, arranged in substantially parallel pairs adjacent the sides of the blank, defining the score lines 131, 132 and 15 133, and 134 and thereby affording flaps 135 at each side of such body portion. These flaps, while not shown in Fig. 2 of the annexed drawings, are folded under the folded laundered shirt, at the back thereof, in the same manner as the flaps 35 20 of the preferred embodiment when applying this modification to a laundered shirt.

In accordance with the present invention, the modification of Fig. 8 is preferably formed with a perforated score line 136 at the juncture of the collar supporting element and the reduced portion 118' of the form, a second perforated score line 136' in close proximity but spaced from the score line 136 and extending in substantially parallel relationship thereto, as well as a third score line 137 at the juncture of the reduced portion 118' with the body portion 118 of the form. The space defined between the two closely adjacent score lines 136 and 136' serves the useful function of permitting the ready folding of the collar supporting element 117 from the outside of the back of a shirt collar 126 of a laundered shirt 127 across the top and into the inside of the shirt collar, see Figs. 2 and 4 of the drawings, when the modified embodiment of Fig. 8 is inserted into operative position with the collar supporting element disposed normal to the body portion 118 and around the inside of the collar 126 adjacent to the neck-band of the shirt, all as indicated in Fig. 2. It is to be observed that the blank 111 is made to the requisite width so that the collar supporting element, when placed in operative position has its ends 128 and 129 lying in close proximity to the lapels 130 of the laundered shirt 127, thus furnishing optimum support for the shirt collar. The notches 140 and 140' in the collar supporting element 117 enhances and facilitates the folding of the collar supporting element and the supporting quality thereof, for shirt collars somewhat higher than average.

In Fig. 9 of the annexed drawings, I have illustrated an alternate form of the modification of Fig. 8 which largely follows such modification but is devised for application to an average height shirt collar, thus eliminating the necessity of the notches in the elongated collar supporting element. Corresponding reference numerals have been utilized to indicate the corresponding parts of the alternation of Fig. 9 to the modification of Fig. 8. Another alternation of the modified embodiment of the invention is illustrated in fragmentary plan view in Fig. 10 where-in the blank 111 has been specially cut or stamped to define a pair of flaps 146 and 147 extending from the reduced portion 118' of the protector form. The flaps 146 and 147 are bendable around the outside of the shirt collar 126, by reason of the provision of the score lines 148 and 149 at the junctures of the flaps with the reduced portion 118', such flaps affording increased strength

or support to the attached shirt collar to obviate any possibility of crushing thereon despite the load of any given bundle of laundered shirts.

It is to be understood that the appended claims are to be accorded a range of equivalents commensurate in scope with the advance made over the prior art.

I claim:

1. A single sheet shirt protector comprising a blank consisting of a relatively large portion for insertion between the folds of a laundered shirt, a reduced extension on one end of said large portion, and an elongated portion on said reduced extension, all of said elements normally lying in a single plane; said blank being scored with a first score line at the juncture of said large portion and said reduced extension, a second score line at the juncture of said reduced extension and said elongated portion, and a third score line in said reduced extension adjacent to but spaced from said second score line, said score lines affording folding of said blank up and over

the back of a collar to bring said elongated portion within the neckband of a collar of a laundered shirt with said elongated portion disposed normal to said large portion.

2. A single sheet shirt protector comprising a blank as defined in claim 1, said elongated portion having an elongated slot therein to permit observation of a laundry mark.

VICTOR AKERS.
